UNITED STATES PATENT OFFICE

2,390,251

CUTTER CHAIN

John A. Hayward, Claremont, N. H., assignor to
 Sullivan Machinery Company, a corporation of
 Massachusetts

Application April 13, 1943, Serial No. 482,875

5 Claims. (Cl. 262—33)

This invention relates to kerf cutting devices, and more particularly to improvements in a reversible cutter chain especially designed for use in the cutting of coal.

An object of the present invention is to provide an improved kerf cutting device. Another object is to provide an improved cutter chain especially designed for use in the cutting of coal. A further object is to provide an improved double-ended, reversible cutter bit. Yet another object is to provide an improved mounting and holding means for a cutter bit. Another object is to provide an improved chain block structure for a cutter chain. A still further object is to provide an improved reversible cutter chain. These and other objects will, however, herein-after more fully appear.

In the accompanying drawing there are shown for purposes of illustration two forms which the invention may assume in practice.

In this drawing:

Fig. 1 is a side elevational view showing a cutter chain constructed in accordance with one illustrative embodiment of the invention.

Fig. 2 is a cross sectional view taken substantially on line 2—2 of Fig. 1, showing parts in front end elevation.

Fig. 3 is a view in longitudinal vertical section taken substantially on line 3—3 of Fig. 2.

Fig. 4 is a detail vertical sectional view taken substantially on line 4—4 of Fig. 3.

Fig. 5 is a horizontal sectional view taken substantially on line 5—5 of Fig. 3.

Fig. 6 is a perspective view of the improved bit holder.

Fig. 7 is a perspective view of the front bit anvil.

Fig. 8 is a perspective view of the improved cutter bit.

Fig. 9 is a top plan view of the clamping bolt.

Fig. 10 is a side elevational view of the clamping bolt shown in Fig. 9.

Fig. 11 is a cross sectional view taken on line 11—11 of Fig. 10.

Fig. 12 is a sectional view similar to Fig. 3, illustrating another embodiment of the invention.

Fig. 13 is a cross sectional view taken substantially on line 13—13 of Fig. 12, with parts shown in front end elevation.

In the illustrative embodiment of the invention shown in Figs. 1 to 11, inclusive, 1 designates a chain block and 2 designates strap links, the latter being pivotally connected at 3 to the chain block. The chain block is of a symmetrical shape and has a lateral lug 4 provided with a socket 5

having its front and rear walls tapering outwardly at 6 near the top of the lug, and open at its sides as shown in Figs. 1 and 4. A longitudinal bore 7 in the lug communicates with the lower portion of the block socket. Received in the block socket is a detachable bit holder 8, while received in the block bore 7 is a clamping bolt 9 for adjusting the holder into bit clamping position. A cutter bit 10 of an improved design is positioned 10 between the holder and a detachable front bit anvil 11, the latter likewise positioned in the block socket. The stem 12 of the bolt 9 is reduced and passes through a bushing 13 fitted in the bore 7 at the rear side of the block socket, and this stem is threaded for engagement with a tightening nut 14 which abuts the rear surface of the block lug 4.

The cutter bit 10 is of the double-ended, reversible "throw away" type, preferably formed by 20 forging, and is generally of trapezoidal shape in side elevation. The bit has a plane front face 15 of elliptical shape terminating in cutting points 16, 16 at the opposite extremities of the bit body. The bit is formed with cutting portions 17 which include the cutting points 16, and these cutting portions are generally T-shape in cross section as shown in dotted lines in Fig. 5. A relatively narrow flange 18 provides the leg of the T at the back of the bit, and this flange 25 is arcuately notched at 19 midway between the ends of the bit. The bit body is thickened in cross section at 20 in adjacency to the notch 19, and the thickened portion has relatively inclined sides. The flange 18 at the back of the bit has 30 inclined end surfaces 21 at the opposite ends of the bit, and these inclined surfaces recede rearwardly from the cutting points 16. In this instance, the cutter bit is located at the longitudinal vertical center of the chain block and the bolt 9 is slotted longitudinally at 22 to receive the inner inactive cutting portion of the cutter bit in the manner shown in Fig. 3.

The holder 8 has an outer head portion 23 and an inner shank portion 24, and the latter portion 45 is formed with a bore 25 through which the clamping bolt 9 extends. The forward portion of the bore 25 is inclined or tapered as shown at 26, and the bolt 9 has a wedge-shaped portion 27 engageable with the walls of the inclined or 50 tapered portion of the holder bore so that when the bolt is moved rearwardly relative to the block, the holder is forced inwardly with a wedging action for a purpose to be later described. The holder head 23 is centrally vertically slotted at 28 at its forward side, and the flange 18 at the

back of the bit is received in this slot. The holder head at the sides of the slot engages at 29 the relatively inclined sides of the central thickened portion 20 of the bit. The holder has a rearward projection 30 received in a vertical slot 31 at the rear side of the block socket for preventing lateral displacement of the holder with respect to the block. The bottom of the holder slot 28 is formed with an arcuate projection 32 which is received in the notch 19 in the bit flange to hold the bit against longitudinal displacement in the holder slot.

The front bit anvil 11 has a forward projection 33 which, at its inner surface 34, rests against the outer surface of the block lug in advance of the block socket in the manner shown in Figs. 1 and 3. The anvil has a shank portion 35 extending into the block socket and slotted at 36 to receive the bolt 9 so that the shank portion of the holder straddles the bolt. The anvil has an inner surface 37 at the bottom of the slot 36 which rests against the upper surface of the bolt, and provides a rearwardly facing, forwardly and outwardly inclined plane surface 38 against which the plane front face 15 of the cutter bit rests. The sides of the bolt are flattened at 39 and the straight sides of the anvil slot 36 engage these flattened surfaces to hold the bolt against rotation. The block socket is vertically slotted or notched at 40 at its forward side, in a manner similar to its rear side, and the front bit anvil 11 may have a projection, similar to the projection 30 on the holder, received in the slot for locking the anvil against lateral displacement. By reversing the bolt, holder and anvil with respect to the block, the cutter bit may be located in a position to cut in the reverse direction in an obvious manner.

In the embodiment of the invention shown in Figs. 12 and 13, the cutter chain is similar to that above described. A cutter bit 41, substantially the same as the cutter bit 10, has its forward face 42 resting against an inclined surface 43 formed directly on the chain block at the forward side of the holder socket. A clamping bolt 44 which is received in the longitudinal block bore is, in this instance, located at one side of the central longitudinal, vertical plane of the block, and the cutter bit is located at the other side of the plane, and the bolt is slabbed off at 45 to clear the inner portion of the cutter bit as shown in Fig. 13. A bit holder 46 is received in the block socket and has an inclined rear surface 47 engaging the rear wall of the socket, and the lower shank portion 48 of the holder is of cylindric shape and is fitted in a vertical bore 49. In this embodiment of the invention the holder and bit cannot be reversed with respect to the chain block due to the arrangement of the bolt and bit at opposite sides of the block.

In both embodiments of the invention the cutter bit, when one point thereof becomes dull, may be released simply by loosening the nut on the clamping bolt and moving the latter forwardly in the block bore to permit outward rectilinear movement of the holder, thereby to release the projection on the holder from the notch at the back of the bit. In the first embodiment the front anvil 11 may be removed upon loosening of the holder, to facilitate removal of the cutter bit. Upon release, the cutter bit may be turned end for end and replaced on the holder, and upon tightening of the bolt the holder is drawn inwardly with a wedging action in the block socket firmly to clamp the bit in cutting position on the

block. When both cutting points of the cutter bit become dull, the bit, due to its inexpensive design, may be discarded. The particular arrangement of the bolt and holder provides an extremely effective bit holding means wherein possibility of the holder becoming loose and lost is substantially avoided. By a simple rearrangement of the parts, in one embodiment, the position of the cutter bit may be reversed on the block. The manner of use and other advantages of the improved cutter chain will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a cutter chain, a chain block having a socket extending substantially at right angles to the path of travel of the chain, said socket having outwardly inclined front and rear walls near the outer end of said socket, a front bit anvil resting on the exterior of said block outside of said block socket and normally stationary with respect to said block, said anvil having a portion projecting into said socket and engaging the front inclined socket wall, a bit holder received in said socket rearwardly of said anvil and engaging the rear inclined socket wall, and means engaging said holder for adjusting the latter inwardly in said socket relative to said anvil to clamp a cutter bit in cutting position against said anvil.

2. In a reversible cutter chain, a chain block having a socket extending substantially at right angles to the path of travel of the chain, said socket having outwardly inclined front and rear walls near the outer end of said socket, said inclined walls each having a narrow vertical recess therein of substantially less width than the width of said socket, a front bit anvil resting on the exterior of said block and normally stationary with respect to said block, said anvil having a portion projecting into said socket and engaging the front inclined socket wall and overlying the front recess, a bit holder received in said socket rearwardly of said anvil and engaging the rear inclined socket wall, said holder having a narrow rearward projection fitting the rear recess for locking said holder against lateral movement with respect to said block, and said holder and anvil being reversible with respect to said block in said socket, and said holder projection engaging said other recess for locking the holder to said block when said holder is in reversed position in said socket, and means engaging said holder in either reversed position thereof in said socket for adjusting said holder inwardly in said socket relative to said anvil to clamp a cutter bit in cutting position against said anvil.

3. In a cutter chain, a chain block having a socket and a longitudinal bore, and a front bit anvil resting against an exterior surface of the block in advance of said socket and having a portion projecting into said socket, a bit holder received in said socket, and a bolt received in said bore and engaging said holder for adjusting the latter rectilinearly inwardly in a direction at substantially right angles to the longitudinal axis of said bolt into a position to secure a cutter bit in cutting position against said anvil, said project-

ing portion of said anvil resting against said bolt in advance of the point of engagement of the latter with said holder.

4. In a cutter chain, a chain block having a socket and a longitudinal bore, and a front bit anvil resting against an exterior surface of the block in advance of said socket and having a portion projecting into said socket, a bit holder received in said socket, and a bolt received in said bore and engaging said holder for adjusting the latter rectilinearly inwardly in a direction at substantially right angles to the longitudinal axis of said bolt into a position to secure a cutter bit in cutting position against said anvil, said projecting

portion of said anvil engaging said bolt to hold the latter against rotation in said bore during adjustment of said holder.

5. A clamping wedge-bolt having a cylindrical body provided with a wedge shaped portion in spaced relation longitudinally from its ends, said bolt body having a longitudinal slot in its upper surface into which the inner portion of a cutter bit is adapted freely to extend, the cylindrical body at the opposite sides of said wedge shaped portion being flattened for engagement with means for holding the wedge-bolt against rotation.

JOHN A. HAYWARD.
